CLAIM

The ornamental design for a configurable table, as shown and described.

DESCRIPTION

FIG. 1 is a top, front, right-side perspective view of a first embodiment of a configurable table;

FIG. 2 is front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a bottom, rear, left-side perspective view thereof;

FIG. 9 is a top, front, right-side perspective view of a second embodiment of a configurable table;

FIG. 10 is a front view thereof;

FIG. 11 is a back view thereof;

FIG. 12 is a left-side view thereof;

FIG. 13 is a right-side view thereof;

FIG. 14 is a top view thereof;

FIG. 15 is a bottom view thereof; and,

FIG. 16 is a bottom, rear, left-side view thereof.

The dash-dash broken lines depict portions of the configurable table that form no part of the claimed design. The dashed-dot broken lines indicate boundaries delineating claimed and unclaimed portions of the configurable table.
